APPARATUS FOR RECLAIMING PACKING
WASTE AND OIL EXTRACTED THERE-
FROM

Harry E. Smith, White Plains, N. Y., assignor to
The New York Central Railroad Company, a
corporation of New York

Application July 5, 1934, Serial No. 733,917

8 Claims. (Cl. 141—2)

This invention relates to an apparatus for reclaiming or renovating packing waste such as is used as packing in journal boxes and the like and for reclaiming the used oil extracted therefrom for further use either in reclaimed condition or by admixture respectively with new or fresh waste and oil.

The object of the invention is to provide an apparatus of this character and for these purposes whereby used packing waste may be reclaimed and the oil carried thereby extracted and both the waste and the oil restored to working condition in a simple, rapid and economical manner for satisfactory reuse, and whereby these results may be efficiently obtained with an elimination of steps of treatment heretofore found necessary to be employed.

In the accompanying drawings,—

Fig. 1 is a schematic plan view, with parts in section, of my improved waste and oil renovating apparatus.

Fig. 2 is a similar view in elevation looking toward the waste renovation side of the apparatus.

Fig. 3 is a view similar to Fig. 2 looking toward the oil-renovating side of the apparatus and the waste saturation vats.

In carrying my invention into practice, drums of inbound, dirty journal box packing are lifted by an overhead hoist or other suitable means and dumped onto a receiving table 1, where the packing is sorted roughly, by hand, to remove the coarser impurities. Thence, the packing is thrown loosely into a first washing vat 2 of a series of spaced washing vats 2, 3, and 4, which is filled with comparatively dirty car oil heated by a submerged steam coil 5. In the vat 2 the packing is allowed to soak for a time, meanwhile being worked in the oil by a hand hook, so as to loosen up and wash out a certain amount of the impurities and oil therein. The packing is then lifted by means of a hand fork or by power lifted tongs and deposited upon a drain-board or pan 2a disposed between the vats 2 and 3 on which it is allowed to rest for drainage by gravity of a portion of the oil therefrom back into the vat 2. The packing is then removed from the board 2a and deposited in the oil in the vat 3 in which it is treated in the same manner as in vat 2. From the vat 3 the waste is then removed and deposited upon a drain-board 3a disposed between the vats 3 and 4 for a similar drainage action of a portion of the oil back into the vat 3. The waste is then washed in the vat 4 in the manner described with reference to vats 2 and 3 and is then transferred

onto a drain-board 4a having portions disposed along the outer end and rear side of the vat 4 on which it rests for a sufficient period to drain a predetermined amount of the oil therefrom, which oil drains back into the vat 4. The drain-boards 2a, 3a, and 4a may be of any suitable form and construction for the purpose and boards 2a and 3a and portions of the board 4a are suitably sloped toward the vats 2, 3, and 4 to serve as supporting guides over which the waste may be drawn in its transfer from vat to vat and to retain and return the oil draining from the waste by gravity to the respective vats and to prevent the oil from slopping onto the floor or other extraneous surfaces. The vat 3 contains a submerged heating coil 6 and the vat 4 a submerged heating coil 7 similar to the coil 5. The form and construction of the board 4a extending around two sides of the vat 4 gives ample space for a loosening up and spreading out of the packing, if desired, to place the packing in condition for further treatment. The vat 3 contains somewhat cleaner oil than the vat 2, while the vat 4 contains somewhat cleaner oil than the vat 3. The coils in these vats are supplied with steam from a suitable source through a steam supply line or lines 8. The working of the packing successively in the vats 2, 3, and 4 gradually and progressively removes therefrom the dirt and other foreign materials and a substantial proportion of the original oil therein, its place being taken by the relatively clean oil from the store in the vat 4. After the packing is worked through the third washing vat 4 it is lifted therefrom and deposited upon the draining board, shelf or pan 4a, where it is allowed to remain sufficiently long to admit of the gravity separation therefrom and return to vat 4, by drainage, of a considerable part of the free oil carried thereby. By the end of that drainage period, the temperature of the oil still retained by the waste has been reduced to a point substantially below that of the oil in the vat 4. The waste so drained and cooled, is then transferred into a centrifuge basket 9 standing on a "balancer" 10. This balancer comprises a support which allows correct distribution of the load in the centrifuge basket. It stands in a pan 11 having an oil drain outlet 12. When loaded, the basket is removed to a centrifuge 13, and revolved therein to remove as much oil as possible from the waste.

The oil in vats 2 and 3 is kept at a temperature of 180-200° F., well below the boiling point of water. The greater part of the water in the packing is settled out in vat 2, and is drawn off

- to a sewer through a valve controlled pipe 14 leading from the bottom of the vat. The oil in vat 4 is kept at a temperature of 230-250° F., and the water remaining in the packing after treatment in the vats 2 and 3 is boiled off in this vat 4. The vats 2, 3, and 4 and boards 2a and 3a and a portion of the board 4a are preferably arranged with the table 1 in longitudinal alinement with each other for the ready and convenient transfer of the waste from one to the other. The board 4a is provided with a chute or the like 15 having a cut-away portion 16 for delivery of the drained waste to the centrifuge basket 9 on the balancer 10.
- 15 Any surplus of oil contained in vat 2 above a predetermined working level escapes via an overflow 17, to a pipe 18, which leads to an unheated, dirty oil sump 19, of small capacity, positioned below the floor level. Similarly the surplus oil 20 contained in vat 3 discharges back into the vat 2 via an overflow 20, while the surplus oil in vat 4 discharges back through an overflow 21 into vat 3, the oil removed from the packing thus traveling back to the vat 2 to keep the oil in the vats 3 and 4 in a comparatively clean condition, while the removed dirt and other foreign particles are deposited to progressive degrees in the vats 2, 3 and 4. The supply of oil in the system of vats is replenished as required with 25 fresh or clean oil, that is, settled oil, from unheated, settling tanks 22, 23, and 24, such replenishing oil being supplied to the vat 4. This replenishing oil flows through a supply line 25, having valved connections 26 with the respective tanks, to a hydrant 27, from which it is drawn into a bucket, the bucket being transported over an overhead monorail line 28 to the vat 4. Water, sediment and dirty oil may be drawn periodically, or whenever required, from the bottoms of vats 2, 3, and 4, through valved pipes 29 to pipes 18 and 18' leading to the dirty oil sump 19, which ordinarily is of about fifty gallons capacity.
- No oil is returned directly from the sump 19 45 to any of the washing vats. From that sump, the oil received is automatically transferred by a pump 30 to an unheated dirty oil storage tank 31, supported with its bottom higher than the tops of the washing vats 2, 3, and 4. From the dirty oil storage tank 31 the oil is transferred to the settling tanks 22, 23, and 24 via a dry-up pan 32, of a construction hereinafter described.
- It will be seen from the foregoing that the waste is first washed in comparatively dirty or 50 impure heated oil in the primary vat or tank 2, whereby a certain proportion of the oil content and foreign materials in the waste are removed therefrom, the waste is then transferred to and washed in heated oil of a somewhat higher degree of purity in the intermediate or secondary vat 3, wherein it is further cleaned, and that the waste is then transferred to and finally washed in the heated oil of a still higher degree of purity in the last vat 4 in which it is cleaned to the 55 finally desired degree for re-saturation with pure oil for use as reclaimed packing. The oil in vats 2 and 3 is heated, as hereinbefore stated, to a suitable cleansing temperature of from 180° to 200° F., at which temperature an efficient cleaning action with the removal of a certain proportion of the moisture content of the packing is obtained, while the oil in the vat 4 is heated to a temperature of from 230° to 250° F., at which temperature a final removal of dirt and oil from 60 the waste is effected and all or substantially all

of the moisture remaining in the waste after treatment in the tanks 2 and 3 driven off. By this stage-by-stage treatment of the waste in a series of heated oil baths of different degrees of purity, beginning with a bath of comparatively dirty oil and ending with a bath of pure or comparatively pure oil, and by replenishing the cleansing oil in the vats in the manner described, substantial and important advantages are gained. The stage-by-stage treatment of the waste in 10 baths of successively increasing oil purity, of which any number may be used, enables even very dirty waste or mixed waste soiled to different degrees to be cleaned to the exact extent desired so that uniform cleaning of all waste in any condition in which it comes to the washer may be effected in a highly efficient and economical manner. As stated, the oil is replenished periodically or as required, in the vat 4 by the addition thereto of pure oil or oil of a certain high degree of purity 15 while the oil in the intermediate vat 3 is replenished therefrom by overflow through the connection 21, and the oil in the vat 2 is replenished from the vat 3 by overflow through the connection 20, the vat 2 being drained of impure oil, 20 the place of which is taken by purer oil from the vat 3, through the overflow connection 17 leading to the dirty oil sump 19. By this means an automatic replenishing of the oil in each vat is obtained by the addition of purer oil from the 25 succeeding vat, the replenishing oil flowing from the final vat to the primary vat in a direction opposite to the direction of progress of the waste, the discharge of oil from each vat occurring as a result of added increment, i. e., replenishing 30 oil, increase of foreign matter removed from the waste, or bulk of waste during a washing action, causing displacement of the oil above its highest working level. The transfer of the waste from a preceding vat from which a portion of the oil 35 has thus been displaced to a following vat will cause a similar overflow of oil thereinto from the following vat to take the place of the oil previously discharged from such preceding vat, so that an automatic gravitational displacement of the oil is 40 effected from tank to tank in inverse order to the travel of the waste as the washing action progresses. The addition of pure oil to the vat 4 may cause at any time, according to quantity 45 supplied, a displacement of oil therefrom into the preceding tank or tanks, according to the condition of the level of the oil in such tanks. This method of washing the waste and replenishing the tanks with oil enables economy in the use of oil to be effected, inasmuch as the same 50 oil is used throughout a series of operations, and it also obviates the necessity of the use of pumps, siphons, or other mechanical transfer devices for circulating the oil, and which are liable in action to stir up the refuse material in the bottoms of 55 the vats and muddy the washing oil in the vats, so that the oil in which the waste is washed will always be maintained at the degrees of purity desired and established for the different washing actions. It will be evident, of course, 60 that this method of replenishing the oil also ensures the maintenance of the oil in the vats at substantially the proper intended differential purity ratios, since the purer oil in one vat somewhat contaminated by a washing action, is displaced into the preceding vat containing washing oil of less purity and so on throughout the 65 series. This replenishing action further tends to secure economy in the use of steam supplied 70

75

to the heating coils in the vats, inasmuch as the hotter oil discharged from the vat 4 into vat 3 and from the latter into the vat 2, assists in maintaining the oil in the latter-named vats at the intended temperatures, so that economy in the use of steam for heating the coils 5 and 6 is ensured. Other advantages of this method are that through the described arrangement of the vats, the washing actions may be successively carried out if desired by direct transfer of the waste over the drainboards without rest for time drainage from vat to vat, thus avoiding the necessity of transferring the waste any considerable distance through the air between spaced vats and causing slopping of the oil over the floor or other surface or undue cooling of the waste from atmospheric exposure during successive washing treatments.

From the centrifuge 13 the basket of extracted waste is lifted and dumped onto the wire-meshed top of one of two portable sorting tables 33 and 34, where it is thoroughly sorted and shaken by hand to remove knots, short threads and dirt. These portable tables 33 and 34 may be moved into and out of working position with relation to a tumbler 35, and said tables are designed to be used alternately in order to give waste resting thereon opportunity to cool. The temperature and moisture content, if any, of the waste on the table 33 or 34 are brought, by the cooling action, to a condition such that no detectable moisture escapes from the waste during the tumbling action which follows. At the end of the cooling period the waste is transferred from the table 33 or 34 to and passed through the unenclosed slowly rotatable, unheated wire-mesh tumbler 35, to fluff it up and complete the removal of short threads and residual dirt therefrom, which may be attained thereby without the assistance of air currents. From the tumbler the waste flows into a sheet metal box 36 and is then in a state ready for re-saturation.

In the operation of re-saturating the cleaned or renovated waste for use, enough clean waste to make one drum of packing is weighed in a sheet metal scoop and placed in a wire-meshed saturation basket which is quickly lowered into an excess of hot oil in one of the saturation vats 37, 38, and 39. After saturation is completed, the basket is hoisted clear of the oil and the surplus oil allowed to drain therefrom. When the draining is nearly completed, or at any time previously, the basket is hung on a crane scale. When the pointer of the scale shows a weight indicative of correct saturation, the basket of re-saturated waste is dumped into a shipping drum and is ready for use in packing journal boxes. New waste may be saturated for use by the apparatus or for admixture with the renovated waste. In preparing the new waste, the waste is pulled out, shaken by hand and the over-length threads cut. The waste is then saturated in one of the saturation vats in the same manner as the renovated waste above described. The renovation of the used oil extracted from the waste is effected in the following manner. From the vat 2 settled water may be drawn off to the sewer via pipe 14, as previously set forth. The dirty oil from vats 2, 3, and 4, balancer 18 and the centrifuge 13, all of which are connected with the drain pipe 18, collects through said pipe to the sump 19. From the sump 19 the dirty oil is delivered by the pump 30 to the overhead dirty oil tank 31. From this tank the oil is transferred through a pipe 40 to the drier pan 32. This pan

is long and shallow and is provided in its bottom with a horizontally disposed steam coil 41 suitably supplied with steam from the steam supply source. The oil flows into one end of this pan through the pipe 40 and travels to the opposite end of the pan. In this pan the oil is subjected to heat of a sufficient degree to boil off any water, if there be any, which remains therein. From the pan 32 the oil flows through pipes 42 having controlling valves 43 therein to the settling tanks 22, 23, and 24, in which it remains quiet for several hours in order to allow all but the finest dirt to settle. The three tanks 22, 23, and 24 are filled, settled and drawn off or emptied in turn. A portion of this settled oil is returned to the washing vat 4 for a vat replenishing action, as previously described.

That portion of the settled oil in the tanks 22, 23, and 24, which is not withdrawn on replenishing the oil in the washing vats, is delivered to a constant level box 44 by an electric pump 45. This pump may be manually thrown into and out of action if desired, but is preferably automatically started and stopped by suitable switch mechanism actuated by a float in the box 44. From the constant level box 44 the oil flows through a superheater 46, which is heated by steam to raise the temperature of the oil to about 300° F., which greatly increases the fluidity of the oil. Thence the hot oil flows through a valve controlled pipe 47 into a pair of super-centrifuge machines 48 of any suitable type, working in parallel. These remove the remaining very finely divided dirt from the oil and vent any vapors, thereby completing the renovation of the oil which is then conducted by gravity through a valve controlled pipe 49 to a storage tank 50. From this tank 50 the oil may be pumped by the pump 51 to the re-saturation vats 37, 38, and 39, for use therein or the oil may first be mixed with other oils, manually supplied to the tank 50, by pumping it out of and then back into that tank by means of pump 51, so that purified renovated oil may be rendered available for use. Any surplus renovated oil which can not be used immediately may be delivered by pump 51 and valved line 52 to an unheated storage tank (not shown) from which it may be supplied for use as occasion requires.

Sediment, including water, if any, and undrained oil accumulating in the settling tanks 22, 23, and 24 may be drawn off through valved line 53 into a filter 54 where the oil is recovered. The filtering medium used in filter 54 may be short thread waste supported on a wire mesh, the oil flowing through the filter by gravity.

It will be observed that the series of vats 2, 3, and 4 and parts cooperating therewith for cleaning and preparing the waste for re-saturation are arranged in a longitudinal row so as to facilitate the transfer of the waste for a step by step treatment from one to the other in a most advantageous manner, while the parts for the renovation of the oil and re-saturation of the waste are arranged in another longitudinal row placed opposite the row of parts for cleaning the waste, while the overhead dirty oil tank is disposed between the primary washing vat and settling tank in the rows, with the overhead monorail extending thereover and over the row of washing vats and related devices, so that the parts employed in the steps of treating the oil are also most advantageously arranged, together with the waste saturating means, to facilitate the work and reduce the amount of labor and time periods involved in the various steps of operation. By this

means, and by the elimination of other steps commonly used, a very compact apparatus capable of being inexpensively installed and operated is provided.

5 From the foregoing description, taken in connection with the drawings, my improved method of renovating waste of the character described and the oil recovered therefrom will be readily understood without a further and extended description, and it will be seen that a method is provided whereby the waste may be readily and efficiently treated to remove all coarse and foreign particles and to extract the oil therefrom, and the waste then re-saturated for further use, in an economical way. Also it will be seen that the invention provides a method and apparatus for efficiently and economically renovating the recovered used oil. The invention further provides a simple, reliable and efficient type of apparatus for the purpose, whereby the operation of recovering the waste and used oil and renovating the same for further use may be performed. By the use of this method and apparatus a number of the steps commonly employed in prior processes for these purposes are eliminated with a reduction in time and course of treatment and amount of working apparatus required. Railroads and other establishments using a large amount of waste for packing purposes may, therefore, reclaim the waste and oil for reuse at a substantial saving by the use of renovated waste and oil, and by the use of my invention effect a substantial saving in the renovating of these substances, in comparison with methods and apparatus for the purpose heretofore in use.

What I claim is:—

1. In an apparatus for reclaiming used packing waste and the like, a series of longitudinally spaced washing vats arranged in following order and successively at increasing elevations between the first and last of the series, the first vat containing a body of washing oil of comparatively low purity and the following vats bodies of oil of increasingly higher purity each with respect to the other, in which bodies of oil differentially graded as to purity the waste is successively washed, means for heating the oil in the vats, means for the discharge of oil rising above a predetermined washing level from the first vat of the series, overflow replenishing connections between the upper portions of the vats of the series for the gravity discharge of oil above a washing level from each vat to a preceding vat, whereby each vat from the last to the first of the series is automatically replenished to maintain a working volume of oil therein and in such manner as to differentially maintain a predetermined ratio of purity of the oil in the respective vats, and sloping drainboards in the spaces between the vats for guiding the waste in its transfer from vat to vat and for supporting the waste and conducting drainage oil therefrom to the preceding vat.

2. An apparatus for treating packing waste for reclamation comprising a series of spaced oil containing washing vats arranged in following order and in gradient relation at different levels from the first to the last of the series, means for heating the oil in the tanks, a sump, means for draining deposits from the bottom portions of the vat to the sump, inclined drainboards bridging the spaces between the vats and forming guiding surfaces over which the waste may be drawn from vat to vat and drain surfaces for the return of oil draining from the waste back into the vat from which it is drawn, an overflow oil discharge

conductor connecting the primary vat of the series at its highest oil level with the sump, and conductors connecting each succeeding vat of the series at its highest oil level with the washing oil containing space of the preceding vat of the series for conducting replenishing oil from vat to vat in the direction opposite to the direction of progress of the waste.

3. In an apparatus for reclaiming used packing waste and the like, a series of oil containing vats arranged in following order to receive the waste and in which the waste is successively washed in the oil to remove the dirty oil and foreign materials therefrom, means for heating the oil in the vats, said vats having overflow connections at different levels for the flow of oil successively from vat to vat throughout the series from the final vat to the first vat of the series, drain boards arranged between the vats of the series and following the final vat for guiding the waste in its transfer from vat to vat and for supporting the waste after each washing action for drainage of oil therefrom, each drain board being arranged to return the drainage oil to the vat in rear thereof in the order of arrangement of the vats.

4. In an apparatus for reclaiming used packing waste and the like, a series of oil containing vats arranged in following order to receive the waste and in which the waste is successively washed in the oil to remove the dirty oil and foreign materials therefrom, means for heating the oil in the vats, said vats having overflow connections for flow of oil successively from vat to vat throughout the series from the final vat to the first vat of the series, means for drawing off dirty oil and refuse from each vat, means for collecting the same and the overflow oil from the first vat, and drain boards between the vats of the series and following the final vat for guiding the waste in its transfer from vat to vat and for supporting the waste after each washing action for the drainage of oil from the waste and return of the drainage oil to the vats.

5. In an apparatus for reclaiming used packing waste and the like, a row of longitudinally aligned and spaced oil containing washing vats adapted to successively receive the waste to be washed in the oil therein, means for heating the oil in the vats, means for withdrawing the oil and impurities therefrom, sloping drain boards disposed in the spaces between the vats of the row for guiding the waste in its transfer from vat to vat and for supporting the waste after each washing action for drainage of oil therefrom and arranged to discharge the drainage oil into the preceding vat, and a drain board having portions arranged at two adjacent sides of the final vat of the row for supporting the waste for a drainage action and having its portions sloping toward said vat.

6. In an apparatus for reclaiming used packing waste and the like, a row of longitudinally aligned and spaced oil containing washing vats adapted to successively receive the waste to be washed in the oil therein, overflow connections between the tops of said vats for the overflow of the oil successively from vat to vat from the final vat to the first vat of the row, means for heating the oil in the vats, means for withdrawing the oil and impurities therefrom, sloping drainboards disposed in the spaces between the vats of the row for guiding the waste in its transfer from vat to vat and for supporting the waste after each washing action for drainage of oil therefrom and arranged to discharge the drainage oil into the preceding vat, and a drainboard having portions arranged at

two sides of the final vat of the row for supporting the waste for a drainage action and having its portions sloping toward said vat.

7. In an apparatus for reclaiming used packing waste and the like, a series of oil containing vats arranged in following order and successively at increasing elevations between the first and last vat of the row, said vats being adapted to receive the waste and in which the waste is successively washed in the oil to remove the dirty oil and foreign materials therefrom, means for heating the oil in the vats, inclined overflow connections between the vats for the overflow of excess oil from each vat to the other from the final to the first vat of the series, and means following each vat of the series and disposed between the same and the succeeding vat for guiding the waste in its transfer from vat to vat and for supporting the waste after each washing action for the drainage of oil from the waste and return of the drainage oil to the vats.

8. In an apparatus for reclaiming used packing waste and the like, a row of longitudinally aligned and spaced oil containing washing vats adapted to successively receive the waste to be washed in the oil therein, said vats being arranged at increasing elevations from the first to the last vat of the series, conductors arranged for the gravity overflow of oil from one vat to the other from the final vat to the first vat of the series, means for heating the oil in the vats, means for withdrawing the oil and impurities therefrom, and sloping drain boards disposed in the spaces between the vats of the row for guiding the waste in its transfer from vat to vat and for supporting the waste after each washing action for drainage of oil therefrom and arranged to discharge the drainage oil into the preceding vat. 5 10 15

HARRY E. SMITH. 20
